FIREPLACE DAMPER

Joseph Koberling, Tulsa, Okla.

Application May 19, 1939, Serial No. 274,632

4 Claims. (Cl. 126—288)

This invention relates to certain new and useful improvements in fireplace dampers.

In the operation of a fireplace, smoke and products of combustion travel upwardly through the chimney with a slow spiral or curling movement and when the outside atmosphere is damp and heavy, there is a tendency for the smoke and products of combustion to be retarded in their up-draft and in effect stifle the up-draft through the chimney with the result that the smoke will descend in the chimney and escape from the fireplace into a room, causing great discomfort to the occupants thereof.

It is therefore an important object of the present invention to provide a fireplace flue damper in which the damper plate has portions thereof bent to impart propeller characteristics to the damper plate whereby impetus will be imparted to smoke and products of combustion passing through the throat of the fireplace at the mounting of the damper to cause the smoke and products of combustion to move upwardly with a spiral twist to overcome the downward damping effects of the outside atmosphere and assure a perfect up-draft through the chimney for a more efficient operation of the fireplace.

The construction of fireplaces greatly varies in design, necessitating numerous differences in walls and other constructions with which the fireplace is associated and the setting of a fireplace in different environments necessitates particular placement of the operating devices for the fireplace damper, it therefore being another object of this invention to so construct the fireplace flue damper that an operating device therefor may be concealed within the fireplace or an operating device may be placed at the front or side of the fireplace for the operation of the damper, the latter being so constructed together with the mounting frame therefor as to adapt the same for the placement of the operating device at the most desirable point.

With the above and other objects in view that will become apparent as the nature of the invention is better understood, the same consists in general of certain novel details of construction and combination of parts hereinafter more fully described, illustrated in the accompanying drawing and claimed.

50 In the drawing:

Fig. 1 is a perspective view of a fireplace flue damper, the damper plate being in its closed position and equipped with a concealed damper plate operator and a front damper plate operator;

55 Fig. 2 is a bottom plan view of the fireplace

damper showing the device to facilitate the attachment of operators of the concealed or exposed front and end operators,

Fig. 3 is a side edge elevational view of the damper plate removed from the supporting frame therefor and showing the propeller formation of the damper plate,

Fig. 4 is a longitudinal detailed sectional view taken on line 4—4 of Fig. 1, showing parts of the front operating device and their connection with the damper plate,

Fig. 5 is a detailed cross-sectional view taken on line 5—5 of Fig. 1, showing an end bearing for the damper plate construction for the operation of an operating device positioned laterally or at the side of the fireplace, and

Fig. 6 is a detailed sectional view showing the connection of the concealed operator rod for the damper plate, the rod being illustrated by dotted lines.

The fireplace flue damper and mounting plate therefor are illustrated as entirely separated from a fireplace and it is to be understood that while this flue damper and supporting structure is shown as being generally of rectangular formation, the same may be constructed in any shape desired to accommodate the mounting thereof in various types of fireplaces and be associated with fireplace or chimney flues of various configurations and of vertical or inclined types.

The damper plate 10 is of generally rectangular formation that is pivotally mounted at opposite ends at axial points in a manner to be presently described with the side edge 11 swung upwardly and the opposite side edge 12 swung downwardly when the damper plate 10 is moved to its open position. The side edge 11 that swings upwardly has rounded corners 13 and 14, the terminal portion of the side edge 11 being of reverse curve formation in simulation of a propeller with the corner 13 slightly extending upwardly while the corner 14 slightly extends downwardly as clearly shown in Fig. 3; this design of the damper plate imparts a spiral motion to the upwardly flowing smoke and products of combustion passing through the throat of the fireplace into the chimney or flue, the spiral activity of the smoke and products of combustion moving with increased inherent velocity due to the spiral motion thereof to increase up-draft through the chimney and to prevent smoking of the fireplace.

A frame is provided for the support of the damper plate 10 and said frame is of generally rectangular formation and comprises a top plate

15 having an opening 16 therein of the general proportions and design of the damper plate 10 with the damper plate axially supported at its opposite ends in a pivotal manner within the 5 frame. As shown more clearly in Fig. 3, a flange 17 of generally rectangular formation in plan view depends from the top plate 15 of the damper plate support in inclosing relation with respect to the damper plate and said flange varies in 10 depth as shown in Fig. 1 so that the same may cooperate with the curved edge 11 of the damper plate to provide a substantially complete closure at the throat of the fireplace. The pivotal mountings for the opposite ends of the damper 15 plate 10 include a bearing 18 at one end of the damper plate and the supporting frame therefor, while the bearing for the opposite end of the damper plate is shown more clearly in Figs. 2 and 5 and comprises a bearing plate 19 secured 20 as at 20 to the bottom face of the damper plate 10 and carrying an outwardly extending cylindrical bearing 21 rotatable in a block 22 anchored between a pair of depending lugs 23 forming a part of the depending flange 17. The 25 bearing plate 19 carries a depending longitudinally extending rib 24 in line with said cylindrical bearing 21, and said rib 24 and bearing 21 are provided with a key socket 25 for purposes presently to appear. Opening movement of the 30 damper plate 10 is limited by abutment lugs 26 projecting into the opening 16 in the damper supporting frame from opposite ends of the top plate portion 15, closing movement of the damper plate 10 being guided by the cut-out portion 27 35 in the side edge 11 of the damper plate that moves over the lug 28 at the adjacent side of the frame plate 15 with said side edge 11 finding rest upon the laterally extending foot 29 carried by the lower end of the lug 28 and disposed 40 at the lower edge of the adjacent portion of the depending flange 17.

The damper is designed to be moved to its open and closed positions by means of a concealed operator located within the fireplace 45 opening, a front operator or one that is operated through the front wall of the fireplace or an end operator that will be referred to as a side operator being operable from the side of the fireplace to effect pivotal movements of the damper plate 50 10 on its end bearings 18 and 21. It is to be understood that the fireplace flue damper is to be equipped with only one operating device 55 thereof, either the concealed, front, or side operator to meet certain conditions or construction of the fireplace, the particular mounting of the damper and the desires of the users thereof.

The concealed operator is shown more clearly in Figs. 1, 2 and 6, and comprises an elongated rod 30 provided with a hook 31 at its upper end 60 engageable in an opening provided in a depending lug 32 carried by the damper plate 10, the lug 32 with an opening therein as shown in Fig. 6 being covered by wear and bearing plates 33. A handle 34 is adjustably mounted on the lower 65 end of the rod 30 and has an arcuate head 35, the concave side thereof being provided with spaced teeth 36. A bracket plate 37 is adapted to be mounted within a fireplace opening and suitably secured to a side wall thereof in concealed position and said bracket plate 37 carries a laterally disposed ring portion 38 in which the handle 34 and arcuate head 35 are disposed, the forward edge of the ring 38 having a struck-up portion 39 with the teeth 36 engageable with the 70 ring 38 at either side of the struck-up portion 39.

according to the mounting of the bracket plate 37 with the struck-up portion 39 acting to restrict movement of the arcuate head 35 relative to the ring 38. The damper is held in its adjusted position by the teeth 36 of the head being engaged with the ring 38, the side edge 11 of the damper plate being slightly overbalanced which combined with the weight of the rod 30 and handle 34, causes the damper plate to have a tendency to move to its closed position which 10 is arrested by the engagement of the teeth 36 with the ring 38.

In lieu of the concealed operator comprising the rod 30 and handle 34 together with its associated bracket plate 37, there may be provided 15 a front operator for the damper plate 10 and one in which the handle of the operator extends through the front wall of the fireplace, such an operator and its connection with the damper plate 10 being shown in Figs. 1, 2, 4 and 5. To 20 accommodate the mounting of the front operator, there is provided a pair of apertured lugs 40 depending from the top plate portion 15 at the end thereof adjacent and laterally of the cylindrical bearing 21 and in which apertured lugs 40 and 25 disk bearings 41 are journaled with key openings in said disk bearings 41 for the reception of an elongated key rod 42 that is interlockingly received therein. An arm 43 having a key bearing 44 at one end is positioned between the apertured lugs 40 and in which the key rod 42 is interlockingly received. The other end of the arm 43 has a link connection 45 with an apertured lug 46 depending from the lower face of the damper plate 10 adjacent the curved edge 11 35 thereof. The outer end of the key rod 42 is provided with a rotatable handle 47 carrying a hand-grip 48 and journaled in a mounting bracket 49. It will be understood that upon rotation of the handle 47 by means of the hand-grip 48 the key rod 42 swings the arm 43 for moving the damper plate 10 on its end bearings 18 and 21, the hand-grip 48 being of a construction for cooperation with the bracket plate 49 for holding the key rod 42 in its rotatably shifted 45 position together with the damper plate 10.

In lieu of either the concealed or front operators for the damper plate 10, a side operator may be provided and this side operator consists of the key rod 42 that is slidably and interlockingly engaged with the key socket 25 in the bearing cylinder 21 at the axial end of the damper plate, the side operator having the handle 41, hand-grip 48, and bracket plate 49 positioned exteriorly of the side wall of the fireplace. 55

From the above detailed description of the invention it is believed that the construction and operation thereof will at once be apparent, it being noted that the spiral formation of the edge 11 of the damper plate imparts spiral activities to smoke and products of combustion flowing upwardly through the fireplace flue or chimney to increase draft through the chimney. It is also to be understood that the fireplace damper is to be equipped with only one of the operating devices, namely, the concealed, front or side operators, the construction of damper plate and mounting frame therefor being of such construction as to permit the selective association therewith of the particular type of operator desired. 60

While there are herein shown and described the preferred embodiments of the invention, it is to be understood that minor changes may be made in the details of construction, such as will 75

fall within the scope of the invention as claimed.

I claim:

- 5 1. In a fireplace damper of the character described, a damper plate having diametrically opposite axial bearings, a mounting frame for the damper plate and one side edge of the damper plate being curved and having rounded ends merging in the end walls of the plate with the rounded ends respectively directed upwardly and 10 downwardly out of the plane of the damper plate in simulation of a propeller to impart impetus and spiral activities to smoke and products of combustion flowing in upward contact therewith.
- 15 2. In a fireplace damper of the character described, a damper plate having diametrically opposite axial bearings, a mounting frame for the damper plate and said damper plate having a 20 reversely curved edge in simulation of a propeller to impart impetus and spiral activities to smoke and products of combustion flowing in upward contact therewith.
- 25 3. In a fireplace damper of the character described, a damper plate having diametrically opposite pivot bearings, a mounting frame for the damper plate, said damper plate having a re-

versely curved edge in simulation of a propeller to impart impetus and spiral activities to smoke and products of combustion flowing in upward contact therewith, concealed damper operating means comprising a rod connected at one end to the bottom face of the damper plate laterally of the longitudinal axis thereof, a bracket plate adapted to be secured to an inner wall of the fireplace and a ratchet head on the lower end of the rod cooperating with the bracket plate for holding the damper plate in adjusted position.

4. In a fireplace damper of the character described, a damper plate having diametrically opposite pivot bearings, a mounting frame for the damper plate and concealed operating means for the damper plate comprising an elongated rod detachably connected at its upper end to the bottom face of the damper plate at one side of the longitudinal axis of the damper plate, a bracket plate secured to an inner side wall of the fireplace and an arcuate ratchet head adjustably mounted on the lower end of the elongated rod and cooperating with the bracket plate for holding the damper plate in adjusted position.
